LINE JUSTIFIER FOR TYPEWRITING MACHINES

Linn Edward Potter, Syracuse, N. Y., assignor to
 L. C. Smith & Corona Typewriters, Inc.,
 Syracuse, N. Y., a corporation of New York

Application October 4, 1939, Serial No. 297,822

9 Claims. (Cl. 197—84)

Important objects of the present invention are to provide, for typewriting and like machines having a traveling carriage, improved line-justifying means of simple and inexpensive construction and designed for convenient manipulation and satisfactory operation; and more specifically, to provide for such machines, an improved escapement rack means adjustable to vary the letter-spacing movement of the traveling carriage 5 in a desired manner for line-justifying.

To these ends, and to other ends which will appear from the following description in detail of a preferred embodiment of the invention shown in the accompanying drawings, the invention 10 consists in the combination of devices, features of construction and arrangements of parts pointed out in the appended claims and set forth in the following description.

In the drawings:

20 Fig. 1 is a top plan view of a rear portion of a typewriting machine equipped with the improved escapement rack means, parts of the machine being in section, and parts broken away;

25 Fig. 2 is a fore-and-aft vertical section on the line 2—2 of Fig. 1 and upon an enlarged scale;

Fig. 3 is a rear view of the escapement rack means and associated elements of the machine, with parts in section and parts broken away;

30 Fig. 4 is a group view of the adjustable rack sections in elevation and out of their mounting, one of said rack sections being shown in operative position between the fixed rack sections; and

35 Figs. 5 and 6 are detail sections on the lines 5—5 and 6—6 respectively, of Fig. 3.

In the drawings the invention is shown embodied in a known typewriting machine, namely an L. C. Smith typewriting machine. There is shown only so much of this machine as is necessary to illustrate the invention in its embodiment 40 therein.

A carriage 10 bearing a platen 11 is supported by bearings 12 upon a main frame 13 for movement transversely of the frame. By spring 45 means, not shown, the carriage is impelled in its step-by-step letter feed movement from right to left, with reference to Fig. 1. For control of said movement there is an escapement mechanism including a toothed escapement wheel 14, a carriage feed pinion 15 rotatable with said wheel and meshing with the escapement rack means, and a stepping dog 16 and a holding dog 17 alternately engageable with the escapement wheel to control step-by-step rotation of the latter in the usual manner. The escapement wheel 55

and feed pinion are affixed to a shaft 18 rotatably supported in a bearing 19 borne by a fixed member 13a of the main frame 13. Dogs 16 and 17 are borne by a rocker 20 pivotally supported upon the frame member 13a. Upon operation of a character key, and upon operation of a space bar of the machine the dog rocker is operated, by means not shown, to shift the dogs for initiation of a tooth space rotation of the escapement wheel and upon release of the 10 key or space bar the rocker is operated to shift the dogs to permit completion of said tooth-space rotation of the escapement wheel, in the usual manner.

The improved escapement rack means with 15 which the carriage feed pinion 15 meshes is provided with an adjustment feature to vary the extent of a number of step-by-step movements of the carriage, for the purpose of justifying lines. Said rack means includes rack sections secured 20 to the carriage in fixed positions and a series of complementary rack sections mounted upon the carriage for adjustment selectively into alignment with the fixed sections to provide for typing either justified lines or for unjustified typing. 25

There are two of the said fixed rack sections designated 21 and 22. Each comprises a straight bar formed of flat metal stock and having along one edge a series of rack teeth 23. The pitch of the teeth upon both bars is the same and is 30 one employed for ordinary letter spacing. There may, for example, be ten of the teeth per inch. Said rack sections are of equal length and their combined length is materially less than the required total rack length. They are mounted 35 upon the carriage in longitudinal alignment and in a spaced relation. The space between their opposed ends may, for instance, be three inches. For supporting said rack sections the carriage is provided with four rearwardly extending rigid 40 bracket arms 24, 25, 26 and 27 spaced along the length of the carriage. These arms may be cast with a longitudinal rear member 10a of the carriage. Near its outer end each bracket arm is formed at its under side with a slot 28. These 45 slots in all of the arms align horizontally along the carriage. Rack bar 21 has its opposite end portions fitted in the slots of the bracket arms 24 and 25 and rack bar 22 has its opposite end portions fitted in the slots of the bracket arms 26 and 27. The opposed inner faces of the bracket arms 25 and 26 are vertical and are spaced apart a distance equal to the aforesaid desired space between the opposed ends of the rack sections. Said opposed ends are disposed flush 50 55

with the said opposed surfaces of the bracket arms 25 and 26. The rack bars are rigidly secured in any suitable manner as by soldering, for example, in the slots in which they are fitted. The teeth of the bars project downwardly from the supporting bracket arms for free meshing with the carriage feed pinion 15. The mounting of the aforesaid adjustable rack sections upon the carriage includes a shaft 29. This shaft is rotatably supported in bearing bores 30 formed in the bracket bars 25, 26 and 27. These bores are located directly over the notches 28 and are in horizontal alinement along the carriage to support the shaft with its axis parallel to the fixed rack sections. The shaft extends from the bracket arm 25 to a point beyond the bracket arm 27 and adjacent to the right hand end of the carriage, with reference to Fig. 1. Between the bracket arms 25 and 26 there is mounted upon the shaft a carrier for the adjustable rack sections. The carrier comprises a cylindrical metal sleeve 31 whose axial bore receives and fits the shaft. A set screw 32 borne by the sleeve serves to lock it to the shaft for rotation therewith. At points equally spaced around its periphery the sleeve is formed with a series of radially disposed slots 33 all of the same dimensions and all extending the entire length of the sleeve, parallel to the shaft axis. In the present instance there are six of these slots. The sleeve is of such length that it fits between the bracket arms 25 and 26, with just sufficient working clearance for rotation of the sleeve. The radius of the sleeve is less than the distance between the shaft axis and the roots of the teeth 23 on the fixed rack bars. The adjustable rack sections are fitted in the slots 33 and rigidly secured by soldering, or otherwise. A knob 29^a is affixed to the outer end 40 of shaft 29 for manually turning the shaft and sleeve 31 and revolvably adjusting the rack sections borne by the sleeve.

There are six of the adjustable rack sections designated 34, 35, 36, 37, 38 and 39. Each comprises a straight bar of flat metal stock formed with teeth along one edge. All of said bars are of the same length as the rotor or sleeve 31, say three inches, and their width is so related to the depth of the sleeve slots 33 in which they are fitted that the crests of the teeth are the same radial distance from the axis of the shaft 29 as the crests of the fixed series of teeth 23. Therefore, by rotation of the shaft any one of the rack sections on the rotary carrier may be adjusted 55 into an operative position between the fixed rack sections and in accurate longitudinal alinement therewith. Any one of the adjustable rack sections so adjusted bridges the gap between the fixed rack sections, and the teeth on the fixed 60 and adjustable rack bar sections are so arranged that the fixed bar sections and the bar section adjusted therebetween will together form a continuous rack.

The teeth 23^a of adjustable rack section 34 have a normal pitch corresponding to that of the teeth 23 on the fixed rack bar sections 21 and 22. Assuming that such pitch provides for ten teeth to the inch the section 34, being three inches in length, will have thirty teeth. When this rack 70 section is in operative position it, in combination with rack sections 21 and 22, forms a rack with teeth of a normal uniform pitch throughout, for normal letter-spacing advance of the carriage in typing. Rack sections 35 to 39 inclusive are line-75 justifying rack sections. The pitch of the teeth

40 of each differs from the pitch of the teeth on all of the other rack sections on the rotary carrier. In the present instance rack section 35 has twenty-nine teeth, section 36 has twenty-eight teeth, section 37 has twenty-seven teeth, section 38 has twenty-six teeth and section 39 has twenty-five teeth. The tooth pitch is uniform along each section and progressively increases from section 34 to section 39. It will be understood, however, that the tooth pitch on the successive rack sections may, instead, progressively decrease from the normal pitch. In either case it will be understood also that the rack teeth and those of the feed pinion 15 will afford sufficient clearance to accommodate the pitch variations. The ordinary escapement means will accommodate such variation.

As previously mentioned, the knob 29^a is turned to bring any desired one of the adjustable rack sections into alinement with the fixed sections 20 21 and 22. Means are provided to indicate which rack section has been so adjusted. Upon the bracket arm 27 there is a fixed index mark 41. Upon the periphery of knob 29^a there is a series of six equally spaced designations: "N," "1," "2," 25 "3," "4" and "5." The location of the mark 41 and the arrangement of said designations are so related to the arrangement of the adjustable rack sections around the shaft axis that when the "N" mark registers with the fixed mark 41 30 the normal-pitch rack section 34 will be in operative position, when mark "1" is in register section 35 will be in operative position, when mark "2" is in register section 36 will be in operative position, and so on for the succeeding marks and 35 the rack sections 37, 38 and 39 respectively.

Automatic snap latching means are also provided for retaining each adjusted rack section in operative position. The bracket arm 27 has a bottomed bore 42 parallel to its shaft bearing 40 and opening toward the adjacent face of the knob 29^a. A lock plunger 43 is fitted in said bore, and has a rounded locking end. A spring 44 within the bore urges the plunger outward toward said face of the knob, and said face has six 45 rounded keeper cavities 45 equally spaced around the axis of shaft 29 and disposed to receive the rounded end of the plunger as the knob is turned. The arrangement of the locking plunger and 50 said cavities around the shaft axis is such with relation to the arrangement of the adjustable rack sections that when any one of the latter has been adjusted to operative position one of the cavities will be in position for the plunger to snap into it. Exertion of twisting force upon 55 the knob will cause the plunger to be cammed back to release position to permit changing of the rack adjustment.

In the employment of the invention for line-justifying, lines may first be typed with the normal-pitch rack section 34 in operative position between the fixed rack sections 21 and 22. Then, choosing the longest line typed as a pattern, the other lines may be evened with it as follows: If a line is found to be one letter space short the 65 knob 29^a is turned to adjust the rack section 35 into operative position. This rack action will so control the carriage advance as to add one letter space to the length of the line in retyping it.

If a line be two letter spaces short the knob 70 is turned to adjust rack section 36 into operative position. Section 36 will control the carriage advance to add two letter spaces to the length of the retyped line. Similarly, adjustment of rack sections 37, 38 or 39 will add three, four or five 75

letter spaces respectively to a retyped line. The structure disclosed provides for line justifying during a medial portion of the carriage travel. That is desirable for the reason that the variation in letter spacing is less noticeable at the middle of a line than at the ends. Another advantage is that it enables the employment of fixed rack sections to hold the carriage stationary at or near either of its limits of travel while the intermediate rack sections are being adjusted relatively to the fixed sections.

It will be seen that the invention provides a line-justifying device which is extremely simple and easy to manipulate and designed for entirely satisfactory service. The device requires a minimum of change in standard typewriter construction and it is designed for very inexpensive manufacture. The rack sections 21, 22 and 34 to 39 inclusive can all be made inexpensively from standard stock of the same width and thickness, and the shaft 29, sleeve 31, knob 29^a and the locking means are all designed for easy and inexpensive manufacture and easy assembly.

What I claim is:

1. A typewriting or like machine having a main frame, a carriage mounted to travel on the frame, and a carriage letter-spacing feed control rack mounted to travel with the carriage, wherein for line justification the rack comprises a rack bar section of flat bar stock having a row of rack teeth of constant pitch along one longitudinal edge thereof and a plurality of additional rack bar sections of flat bar stock each having a row of rack teeth of constant pitch along one longitudinal edge thereof, the tooth pitch of one of said additional rack bar sections corresponding with that of the first-mentioned section and the tooth pitch of each of the others of said additional rack bar sections being different from that of the remainder thereof, and means are provided for supporting said plurality of additional rack bar sections for selective shifting of different ones thereof into operative longitudinal alignment with said first-mentioned rack bar section to form therewith a longer continuous rack.

2. A typewriting or like machine as claimed in claim 1, wherein the said plurality of additional rack bar sections are mounted in circumferentially spaced longitudinal slots in a rotary carrier which is supported on the carriage for rotation about a longitudinal axis extending parallel to the path of travel of the carriage and longitudinally of and parallel to the said first-mentioned rack section.

3. In a typewriting or like machine having a carriage traveling on a frame, and escapement means, escapement rack means borne by the carriage to cooperate with said escapement means to control travel of the carriage and comprising a pair of thin bar rack sections each having teeth along one longitudinal edge and secured to the carriage in a fixed position longitudinally spaced and longitudinally aligned, said rack sections having teeth of the same pitch on both sections, a rotor mounted upon the carriage and extending along the space between said rack sections and having means at one end of the carriage for rotating it, bearings for said rotor mounted on the carriage, and a series of intermediate thin bar rack sections each rigidly secured to and extending lengthwise of said rotor, all of said series of racks being of the same thickness as the fixed rack sections with the teeth thereof radially disposed to align with the end teeth of the fixed

rack sections upon rotation of the rotor, and one having teeth of the same pitch as that of the teeth of said first rack sections and each of the others having teeth of a pitch different from that of the teeth of said first sections and different from the pitch of the teeth of the remaining intermediate rack sections, for line justifying, and any one of said intermediate sections being adjustable, by rotation of said rotor, into an operative position between and in longitudinal alignment with the ends of said fixed sections to place the end teeth thereof in matching relation to the end teeth of the said fixed sections to form therewith a continuous thin bar rack.

4. In a typewriting or like machine having a carriage traveling on a frame, and escapement means, escapement rack means borne by the carriage to cooperate with said escapement means to control travel of the carriage and comprising a pair of thin bar rack sections each having teeth along one longitudinal edge and secured to the carriage in a fixed position longitudinally spaced and longitudinally aligned, said rack sections having teeth of the same pitch on both sections, a shaft rotatably mounted upon the carriage and extending along the space between said rack sections and along one of said rack sections to a point adjacent one end of the carriage and at said point having a knob for rotating it, bearings for said shaft mounted on the carriage, a sleeve affixed to the portion of the shaft extending along said space between said pair of rack sections, means to hold said sleeve against longitudinal shifting with respect to the fixed rack sections, said sleeve being formed with a series of longitudinal slots spaced around its periphery, and a series of intermediate thin bar rack sections each rigidly secured in one of said slots and extending lengthwise of said shaft, all of said series of racks being of the same thickness as the fixed rack sections with the teeth thereof radially disposed to align with the teeth of the fixed rack sections upon rotation of the rotor, for line justifying, and any one of said intermediate sections being adjustable, by rotation of said shaft, into an operative position between and in longitudinal alignment with the ends of said fixed sections to place the end teeth thereof in matching relation to the end teeth of the said fixed sections to form therewith a continuous thin bar rack.

5. In a typewriting or like machine having a carriage traveling on a frame, and escapement means, escapement rack means borne by the carriage to cooperate with said escapement means to control travel of the carriage and comprising a thin bar rack section having teeth along one longitudinal edge and secured to the carriage in a fixed position and extending inwardly from one side of the carriage, a rotor mounted on the carriage adjacent the inner end of said fixed rack section for rotation about an axis extending along said fixed section, rigid bearings for said rotor mounted on the carriage, means to hold the rotor against longitudinal shifting with respect to the fixed rack section, and a series of complementary thin bar rack sections rigid with said rotor and spaced around the periphery thereof, and all of said complementary racks being of the same thickness as the fixed rack section with the teeth thereof radially disposed to align with the teeth of the fixed rack section upon rotation of the rotor, and any one of the complementary sections being adjustable, by rotation of said rotor, into an operative position in longitudinal alignment with said fixed rack section with one

end of the adjusted complementary rack flush with the adjacent inner end of the fixed rack to form therewith a continuous thin bar.

6. In a typewriting or like machine having a carriage traveling on a frame, and escapement means, escapement rack means borne by the carriage to cooperate with said escapement means to control travel of the carriage and comprising a thin bar rack section having teeth along one longitudinal edge and secured to the carriage in a fixed position and extending inwardly from one side of the carriage, a rotor mounted on the carriage adjacent the inner end of said fixed rack section for rotation about an axis extending along said fixed section, bearings for said rotor mounted on the carriage one of said bearings being located at the inner end of the fixed rack section and forming a rigid abutment to hold the rotor against longitudinal shifting in one direction with respect to the fixed rack section, the inner end of said fixed rack section extending across the said adjacent rigid abutment and rigidly secured thereto with its teeth projecting beyond the surface of said abutment and with the inner end of said rack section flush with the inner surface of said abutment, and a series of complementary thin bar rack sections rigid with said rotor and spaced around the periphery thereof, one end of each of said complementary rack sections being flush with the inner surface of said rigid bearing abutment and all of said complementary racks being of the same thickness as the fixed rack section with the teeth thereof radially disposed to align with the teeth of the fixed rack section upon rotation of the rotor, and any one of the complementary sections being adjustable, by rotation of said rotor, into an operative position in longitudinal alignment with said fixed rack section with one end of the adjusted complementary rack flush with the adjacent end of the fixed rack to form therewith a continuous thin bar rack.
7. In a typewriting or like machine having a carriage traveling on a frame, and escapement means, escapement rack means borne by the carriage to cooperate with said escapement means to control travel of the carriage and comprising a thin bar rack section having teeth along one longitudinal edge and secured in a fixed position and extending inwardly from one side of the carriage, a rotor mounted on the carriage adjacent the inner end of said fixed rack section for rotation about an axis extending along said fixed section, bearings for said rotor mounted on the carriage one of said bearings being located at the inner end of the fixed rack section and forming a rigid abutment, the inner end of said fixed rack section extending across the said adjacent rigid abutment and rigidly secured thereto with its teeth projecting beyond the surface of said abutment and with the inner end of said rack section flush with the inner surface of said abutment, and a series of complementary thin bar rack sections rigid with said rotor and spaced around the periphery thereof, all of said complementary racks being of the same thickness as the fixed rack section with the teeth thereof radially disposed to align with the teeth of the fixed rack section upon rotation of the rotor, and all of said complementary rack sections being so arranged that one end will be flush with the inner end of the fixed rack section when aligned therewith, and any one of the complementary sections being adjustable, by

rotation of said rotor, into an operative position in longitudinal alignment with said fixed rack section with one end of the adjusted complementary rack flush with the adjacent end of the fixed rack to form therewith a continuous thin bar rack.

8. In a typewriting or like machine having a carriage traveling on a frame, and escapement means, escapement rack means borne by the carriage to cooperate with said escapement means for controlling travel of the carriage and comprising a pair of thin flat rack bar sections rigidly secured to the carriage in constant longitudinal alignment and spaced apart longitudinally and having teeth of the same pitch, and a plurality of intermediate thin flat rack bar sections of the same thickness as said pair of racks, including a section having teeth of the same pitch as the teeth of said first rack sections and a line-justifying rack section having teeth of a different pitch, and a mounting for said intermediate rack sections supporting them on the carriage for revolving relatively to said first sections for adjustment of one or the other of said intermediate sections selectively into an operative position between and in longitudinal alignment with said first sections to form therewith a thin flat continuous rack of uniform thickness.

9. In a typewriting or like machine having a carriage traveling on a frame, and escapement means, escapement rack means borne by the carriage to cooperate with said escapement means to control travel of the carriage and comprising a pair of thin bar rack sections each having teeth along one longitudinal edge and secured to the carriage in a fixed position longitudinally spaced and longitudinally aligned, said rack sections having teeth of the same pitch on both sections, a shaft rotatably mounted upon the carriage and extending along the space between said rack sections and along one of said rack sections to a point adjacent one end of the carriage and at said point having a knob for rotating it, rigid bearings for said shaft mounted on the carriage at the inner ends of the fixed pair of rack sections, the inner ends of said pair of rack sections being secured to and extending across said bearings and terminating flush with the inner surfaces of said bearings, a sleeve affixed to the portion of the shaft extending along said space between said bearings and said pair of rack sections, and having its ends abutting the inner sides of said bearings to hold said sleeve against longitudinal shifting with respect to the fixed rack sections, said sleeve being formed with a series of longitudinal slots spaced around its periphery, and a series of intermediate thin bar rack sections each rigidly secured in one of said slots and extending lengthwise of said shaft with its ends flush with the inner sides of said bearings, all of said series of racks being of the same thickness as the fixed rack sections with the teeth thereof radially disposed to align with the teeth of the fixed rack sections upon rotation of the rotor, for line justifying, and any one of said intermediate sections being adjustable, by rotation of said shaft, into an operative position between and in longitudinal alignment with the ends of said fixed section to place the end teeth thereof in matching relation to the end teeth of the said fixed sections to form therewith a continuous thin bar rack.
